WIPI NG MECHANISM FOR INTAGLIO
PRINTING PRESSESArthur M. Wickwire, Jr., Mountain Lakes, N. J.,
assignor to Chambon Corporation, Garfield,
N. J., a corporation of New York

Application June 22, 1938, Serial No. 215,079

12 Claims. (Cl. 101—157)

This invention relates to intaglio printing presses and particularly to an improved wiping mechanism and manner of mounting said mechanism on such a press and applying the desired pressure thereto.

In gravure or intaglio printing, the ink or other marking material is supplied to the printing cylinder in greater quantities than actually needed for printing. The excess ink is then removed by a wiping device or doctor blade, usually in the form of a thin flexible steel blade, which is arranged to contact the printing cylinder throughout the length thereof and exert a scraping action on the surface of the cylinder. It is essential that the doctor blade bear against the surface of the cylinder uniformly throughout its length in order that all excess ink will be removed and the desired uniform quantity will remain in the cells of the engraving. Any non-uniformity of pressure is liable to cause detrimental wear in portions of the engraving and the blade or a slight buckling or rippling of the blade so that in certain portions thereof it may not contact the engraving at all.

In the past, various means have been suggested for producing proper pressure in the doctor blade. The simplest and most common arrangement has consisted of weights suspended from levers provided at each end of the doctor blade; or springs provided at each end. Other pressure applying means have consisted of rather cumbersome superstructures arranged above the doctor blade for contacting it throughout its length. Practically all of these devices, however, have either been complicated mechanically or required control at two or more places to effect an adjustment of pressure. Moreover, with many of them it has been impossible or impracticable to make a desired adjustment of pressure while the press is in operation.

I have found that these and other difficulties may be obviated and uniform pressure may be applied at both ends of a doctor blade by a simple mechanism having a single adjusting means which is readily accessible during operation of the press.

In accordance with my invention, in one form thereof which I now consider most desirable, pressure is applied uniformly and simultaneously at both ends of the doctor blade holder by means of a single spring which is so arranged that the tension thereof may be regulated from a convenient place while the press is operating. The single tension spring may be arranged in any convenient location, and the pressure created

thereby transmitted through cables and pulleys to cranks and links associated with the doctor blade holder. The pressure transmitting system includes two pulleys, one of which may be moved with respect to the other to increase or decrease the tension in the spring.

The above and other features and objects of the invention will be apparent from the following description and the accompanying drawings, in which:

Fig. 1 is a plan view showing the entire construction;

Fig. 2 is an enlarged vertical sectional view taken substantially along the line 2—2 of Fig. 1, and showing the doctor blade in inoperative position;

Fig. 3 is a front elevational view, partly in section, taken substantially along the line 3—3 of Fig. 1;

Fig. 4 is a vertical sectional view, taken substantially along the line 4—4 of Fig. 1, and showing the doctor blade in operative position;

Fig. 5 is a fragmentary plan view, with portions broken away and in section, of the double pulley mechanism for adjusting the spring tension;

Fig. 6 is a longitudinal vertical sectional view taken substantially along the line 6—6 of Fig. 5; and

Fig. 7 is a transverse vertical sectional view taken substantially along the line 7—7 of Fig. 6.

I have shown the features of my invention embodied in an intaglio printing machine of the general type disclosed in my copending application Ser. No. 217,139 filed July 2, 1938, only so much of the machine being shown herein as is necessary for an understanding of the present invention. It is to be understood, however, that the invention is not restricted in its use to such a machine, but the principal features thereof may be used in intaglio printing machines generally.

Referring now to the drawings, and particularly Figs. 1 and 2, it will be observed that the intaglio printing machine comprises side frames 10 having horizontally disposed portions or members 12, in which is journalled the shaft of an engraved printing cylinder 14. Ink is supplied to the surface of the printing cylinder in quantities greater than required for printing and all excess ink is removed by means of a wiping mechanism which is designated as a whole by the reference numeral 16 and is adapted to condition the engraved cylinder for printing. It is the arrangement and manner of mounting the wiping

mechanism which forms the subject matter of my present invention.

As shown, the wiping mechanism comprises a suitable laminated doctor blade 18 which may be 5 removably secured, as by means of screws 20 (Figs. 1 and 3), in a doctor blade holder 22. If desired, a deflector 23 may be secured to the doctor blade holder so that when the doctor blade is in operative position (Fig. 4) any ink which may 10 be thrown from the rotating printing cylinder will not come in contact with said doctor blade holder and the mechanism adjacent thereto. The doctor blade holder is provided with suitable trunnions 24 at each end thereof and these are 15 journaled in bearings 26 provided on depending brackets 28 secured to, or formed integrally with, a slidable supporting member 30. Supporting member 30 is rectangular in cross-section and is received in similarly shaped openings 32 provided 20 in adjustable supporting blocks 34. At one side of the press the supporting member 30 may be extended beyond the horizontal frame member 12 and there connected to an actuating member 36 (Fig. 3) which is adapted, in a well known manner, to impart a reciprocating movement to 25 the supporting member so as to reciprocate the doctor blade 18 across the surface of the printing cylinder.

Supporting blocks 34, which rest on the top 30 surfaces of the horizontal frame members 12, are provided at each side thereof with upwardly projecting flanges 36 which slidably engage the side edges of an inverted U-shaped retaining bracket 38 fastened to the associated horizontal frame 35 member 12 by means of screws 40. Thus, the supporting blocks may be moved along the horizontal frame members 12 toward and away from the printing cylinder so that the position of the entire wiping mechanism may be adjusted for 40 cylinders of different diameters. For effecting such movement of the supporting blocks 34, each block may be provided with a lug 42 having a threaded opening therein for receiving the reduced and threaded end 44 of a shaft 46 which is 45 journaled in a suitable bearing provided in a lug 48 formed on the bracket 38. The end of the shaft 46 opposite the threaded end 44 has a suitable spiral bevel gear 50 fixed thereon by means of a nut 52 and cooperating with a gear 54 mounted on a shaft 56. This shaft is suitably 50 journaled in the brackets 38 and at one end thereof may be provided with a crank 58 so that it may be readily turned to effect the above-mentioned movement of the supporting blocks 55 through the gears 54, spiral bevel gears 50 and threaded shaft end 44 in an obvious manner.

When the wiping mechanism is moved to the desired position with reference to the printing cylinder 14 by turning the crank 58, the doctor blade holder may be rotated from the inoperative 60 position shown in Fig. 2 to the operative position shown in Fig. 4. To accomplish this, each trunnion 24 has a crank member or arm 60 mounted thereon. At the outer end of each crank 60 65 there is a headed pin 62 which is received in an elongated slot 64 provided in one end of a link 66. The other end of each link 66 is curved and pivotally connected to a crank member or arm 68 mounted on a shaft 70 which is journaled in 70 special left and right hand brackets 72 and 74 respectively (Fig. 1), secured in any suitable manner to the slidable supporting member 30. At one end, the shaft 70 extends beyond the side frames 10 and through an opening provided in 75 an upstanding flange 76 formed on the end of

the supporting member 30. A hand lever or crank 78 is secured to this end of the shaft 70 and by turning it the doctor blade may be moved from the Fig. 2 position to its operative position as shown in Fig. 4.

It will be noted in Fig. 4 that when the doctor blade is in operative position, the pin 62 may move in either direction in the slot 64 without touching the ends of said slot. This is desirable in order that the doctor blade holder 22 may be 10 moved or rotated slightly to produce the necessary pressure of the doctor blade 18 against the surface of the printing cylinder 14. I have provided a novel mechanism for producing this pressure, which mechanism will now be described.

As best shown in Fig. 3, the trunnion 24 at the right hand end of the doctor blade holder 22 (the left hand end in Fig. 1) has a segmented pulley 80 mounted thereon. A cable or cord 82 is fastened at one end in any suitable manner in the lower extremity of the segmented pulley groove and extends upwardly over a pulley 84 which is horizontally pivoted in a housing 86 secured to the supporting member 30 adjacent the special bracket 72. The cable 82 then extends substantially horizontally across the supporting member 30 and above the shaft 70 and has its other end connected to one end of a suitable floating tension spring 88. Similarly, the trunnion 24 at the left hand end of the doctor blade holder 22 has a 20 segmented pulley 90 mounted thereon; and a cable 92 fastened thereto passes upwardly over a pulley 94 pivoted in a housing 96 mounted on the supporting member adjacent the bracket 74 25 and is connected to the opposite end of the tension spring 88. Openings 98 (Figs. 2 and 4) may be provided in the slidable supporting member 30, so that the cables 82 and 92 may pass substantially vertically upward to their associated pulleys 84 and 94 respectively.

By mechanism just described, the force created by the single tension spring 88 may be transmitted to each end of the doctor blade in equal amounts so as to create a uniform pressure of the doctor blade against the surface of the printing cylinder, the amount of pressure created depending on the size and characteristics of the spring 88. In order to permit adjustments in the pressure of the doctor blade, I have provided an adjusting mechanism 100 by means of which the 50 tension in the spring 88 may be varied.

As best shown in Figs. 5, 6 and 7, this adjusting mechanism comprises a substantially rectangular block-like housing 102 having an integrally formed standard 104 which is attached to the slidable supporting member 30 by means of screws 106. The cable 92 may be passed through an opening 108 which extends from the outside wall into a recess 110 in which is mounted a supporting block 112. A pulley 114 is rotatably mounted on a pin or shaft 116 secured to the block 112 and the cable 92 passes around this pulley and onto a pulley 118. This latter pulley is rotatably mounted on a pin 120 fixed in a block 122 which is slidably received in a longitudinal groove 124 provided in the housing 102. From the pulley 118, the cable extends out of the housing 102 and to the spring 88. If desired, the top of the housing may be closed with a cover 126.

For moving the block 122 in the groove 124, said block is provided with a threaded opening 128 in which is received the threaded reduced end 130 of a shaft 132. This shaft, adjacent the threaded end thereof, rotates in a bearing pro- 75

vided in a lug 134 formed on the end of the housing 102, and extends outwardly through an opening provided in the flange 76 of the supporting member 30. A collar 136 is fixed on the shaft adjacent the lug 134 for maintaining said shaft in proper position; and a hand wheel 138 may be provided at the outer end of the shaft to facilitate turning it. It will be apparent that by turning the handwheel 138 the block 122 may be moved either to the right, as shown in Fig. 5 so as to increase the tension in the spring 88, or to the left so as to decrease the tension of said spring. In this manner the pressure with which the doctor blade contacts the surface of the printing cylinder may readily be varied. It is to be noted that all of the adjusting mechanism is carried by the slidable supporting member 30 so that, even though said member is reciprocating, adjustments in the doctor blade pressure may be made while the press is in operation.

Although I have described herein a preferred embodiment of my invention, it will be understood that various changes may be made in the construction and certain features may be employed without others, without departing from the invention or sacrificing any of its advantages.

What I claim is:

1. In an intaglio printing machine, the combination with a doctor blade of a single resilient means for applying pressure equally to both ends of said doctor blade.

2. In an intaglio printing machine, the combination with a doctor blade of a single spring for applying pressure equally to both ends of said doctor blade and means for regulating such pressure.

3. In an intaglio printing machine, a printing cylinder, a doctor blade mounted for pivotal movement toward and away from said printing cylinder, and a single spring for applying pressure to said doctor blade in equal amounts at each end thereof.

4. In an intaglio printing machine, a pair of side frames, a printing cylinder journalled in said frames, a supporting member mounted on said frames, a doctor blade holder pivotally mounted on said support and having a doctor blade mounted therein, and a single spring arranged for applying rotative force to said doctor blade holder at each end thereof.

5. In an intaglio printing machine including a printing cylinder, a unitary wiping mechanism comprising a support, a doctor blade holder pivotally mounted on said support, said holder being adapted to be rotated into wiping contact with said printing cylinder and having a doctor blade mounted therein, and a single spring for applying rotative force to said doctor blade holder at each end thereof for producing pressure in said doctor blade against said printing cylinder.

6. In an intaglio printing machine including a printing cylinder, a unitary wiping mechanism comprising a support, a doctor blade holder pivotally mounted on said support, said holder being adapted to be rotated into wiping contact with said printing cylinder and having a doctor blade mounted therein, a single spring for applying rotative force to said doctor blade holder at each end thereof for producing pressure in said doctor blade against said printing cylinder, and means for regulating the tension in said spring so as to vary such pressure.

7. In an intaglio printing machine including a printing cylinder, a unitary wiping mechanism comprising a support; a doctor blade holder pivotally mounted on said support and having a doctor blade mounted therein, said holder being adapted to be rotated into wiping contact with said printing cylinder; and means for applying rotative force to said doctor blade holder, said means comprising a tension spring having one end connected by a cable to one end of the doctor blade holder and the other end connected by a cable to the other end of said doctor blade holder.

8. In an intaglio printing machine including a printing cylinder, a unitary wiping mechanism comprising a support; a doctor blade holder pivotally mounted on said support and having a doctor blade mounted therein, said holder being adapted to be rotated into wiping contact with said printing cylinder; and means for applying rotative force to said doctor blade holder, said means comprising a tension spring having one end connected by a cable to one end of the doctor blade holder and the other end connected by a cable to the other end of said doctor blade holder, and means for adjusting the tension of said spring.

9. In an intaglio printing machine including a printing cylinder, a unitary wiping mechanism comprising a support; a doctor blade holder pivotally mounted on said support and having a doctor blade mounted therein, said holder being adapted to be rotated into wiping contact with said printing cylinder; and means for applying rotative force to said doctor blade holder, said means comprising a tension spring having one end connected by a cable to one end of the doctor blade holder and the other end connected by a cable to the other end of said doctor blade holder, one of said cables passing around a pair of relatively adjustable pulleys located between the spring and doctor blade holder.

10. In an intaglio printing machine including a printing cylinder, a unitary wiping mechanism comprising a support; a doctor blade holder pivotally mounted on said support and having a doctor blade mounted therein, said holder being adapted to be rotated into wiping contact with said printing cylinder; and means mounted on said support for applying rotative force to said doctor blade holder, said means comprising a single tension spring arranged so that the force thereof may be transmitted through cables and pulleys to said doctor blade holder, such force transmitting system including two pulleys, one of which is adjustable with respect to the other for varying the tension in said spring.

11. In an intaglio printing machine, the combination with a doctor blade of a single resilient means disposed between the ends of the doctor blade and arranged to apply pressure simultaneously and in equal amounts to both ends of said doctor blade.

12. In an intaglio printing machine, the combination with a doctor blade of a single resilient means disposed between the ends of the doctor blade and arranged to apply pressure simultaneously and in equal amounts to both ends of said doctor blade, and means for regulating said single resilient means so as to vary the amounts of pressure so applied.

ARTHUR M. WICKWIRE, JR.
